CLAIM

The ornamental communication device, as shown and described.

DESCRIPTION

FIG. 1 is a perspective view of a first embodiment of an ornamental communication device.

FIG. 2 is a front view of the first embodiment thereof.

FIG. 3 is a rear view of the first embodiment thereof.

FIG. 4 is a first side view of the first embodiment thereof.

FIG. 5 is a second side view, opposite the first side view, of the first embodiment thereof.

FIG. 6 is a bottom view of the first embodiment thereof; and, FIG. 7 is a top view, opposite the bottom view, of the first embodiment thereof.

The broken line portions of the drawings form no part of the claimed design or a specified embodiment thereof.
